(57) **CLAIM**

The ornamental design for a dispenser, as shown and described.

DESCRIPTION

FIG. 1 is an isometric view of a top, front, and right side of an ornamental design for a dispenser;

FIG. 2 is a front elevational view of the dispenser of FIG. 1; FIG. 3 is a rear elevational view of the dispenser of FIG. 1; FIG. 4 is a right side elevational view of the dispenser of FIG. 1;

FIG. 5 is a left side elevational view of the dispenser of FIG. 1; and,

FIG. 6 is a top plan view of the dispenser of FIG. 1. In the drawings, the broken lines depict environmental subject matter only and form no part of the claimed design.

1 Claim, 5 Drawing Sheets# US D834,168 S
